UNITED STATES PATENT OFFICE.

ERWIN AUFFURTH, JR., AND ERICK HJERPE, OF PORT ARTHUR, TEXAS.

GAME.

1,386,594.

Specification of Letters Patent.

Patented Aug. 9, 1921.

Application filed September 4, 1920. Serial No. 408,245.

To all whom it may concern:

Be it known that we, ERWIN AUFFURTH, Jr., and ERICK HJERPE, citizens of the United States, residing at Port Arthur, in the county 5 of Jefferson and State of Texas, have invented certain new and useful Improvements in Games, of which the following is a specification.

This invention relates to games.

10 An object of this invention is to provide an amusement device in the nature of a game of skill, rather than a game of chance, which is up to date in appealing to the current taste for aeroplane devices and provides an 15 attractive and interesting reward for the successful contestant and one in which there is apparent to the player no possible chance of trickery or the showing of favoritism.

It is a further object of this device to provide 20 an easily portable, quickly installed and inexpensively constructed device of this character and to provide a game thrilling to the players and spectators and also to provide a game, the duration of which may be 25 controlled, whereby when there is a limited gathering of spectators or players, the game may be prolonged and whereby it may be shortened to accommodate a greater number of players and increase the money returns 30 to the operator.

With these and other objects in view, the invention consists in the construction, the combination, the detail and arrangement of parts as hereinafter more fully described 35 and claimed.

In the drawings,

Figure 1 is a side elevation, partly in section, of our improved game,

Fig. 2 is a section at 2—2 of Fig. 1,

40 Fig. 3 is a perspective of a part of the aeroplane, showing in detail the candy releasing mechanism,

Fig. 4 is a fragmentary section at the top center of this device, and

45 Fig. 5 is a fragmentary section at the bottom center of this device.

In the embodiment of our invention, there is provided a set of legs 2 supporting a plurality of spokes 3 on stand 6 provided with 50 braces 4, interconnecting the inner legs 2 mounted at the four corners of the said stand 6, the said spokes 3 being bolted or otherwise suitably fixed to the said stand 6 and also bolted or otherwise suitably fixed 55 to a center plate 7, reinforcing the central portion of the table 6, which plate 7 is cen-

trally bored and has affixed thereto in said bore, a tubular member 14 upwardly extending and forming a journal for a shaft 15, preferably of wood. The entire height of 60 the apparatus is preferably about eight feet, the said tubular member extending to the top thereof and protruding slightly below the bottom thereof. The said tubular member 14 is provided with a cap 30, screw-threaded thereon, which cap 30 journals a stub shaft 29, which stub shaft 29 is provided at one end with a taper screw and at the other with a screw provided with a shoulder, the taper screw screwing into the 65 top of the said shaft 15 and also screwing into the center of a cross-arm 23, which is preferably inclosed in wicker or may be made of cane, and is preferably of a length of about five feet. The bottom of the said 70 shaft 15 is provided with a metallic insert 10, which insert 10 serves as the bottom shaft and is mounted against the downward thrust in a ball bearing pulley or roller 5, the said bottom end of the insert being pointed 75 and providing a point bearing in a concave part of the top of the roller 5, thereby providing a double means of preventing friction, the whole shaft 15 together with the revolute members mounted thereon being 80 carried upon this point upon the insert 10. Further cataloging the parts, the numeral 85 11 indicates nets into which candy drops, as hereinafter more fully described, there being thirty-two nets in all, the numeral 12 90 indicating timber partitions, the numeral 13 indicating a chain leading to the brake, 16 is an aeroplane, 17 indicates chains on which the plane is suspended from the cross-arm, 18 is a chain which trips candy as the plane 95 swings out in flight, 19 is a candy trip spring and weight showing chain taut in flight, 20 is a candy cradle, 21 is a motor with air blade, also acting as counterbalance, 22 is a fiber brush mount, 24 is a wire support to 100 prevent the arm from bending, 25 is a wood prop to support the wire support, 26 indicates 110 volt wire leads to motor and plate, 27 indicates copper friction brushes transferring the distributing current to plate and 105 motor, 28 indicates copper rings with 110 volt wire leads to brushes, 31 indicates 4 volt electric lamps which illuminate the plane in flight, 32 indicates a stepdown transformer, stepping down from 115 volts 110 to 4, 8 and 12 volts for small lights, 33 indicates 110 volt A. C. and D. C. sixty cycle

motor in plane, 34 indicates wire leads from switch to plane and motor. A weight 35, attached to the candy trip, returns the bottom to the cradle and all that is needed is to 5 replace the fallen box. In operation, the whole structure stands from tip to tip, about eight feet. The netting or basket circle is about eleven feet. The mechanism of this game is not cog driven, but absolutely self-propelled by two motors, one in the plane and one on the other end of the cross-arm. 10 115 or 110 volts A. C. or D. C. current can be used. There are thirty-two six inch paddles which correspond to thirty-two nets. 15 The candy, one-half pound, is then placed into the cradle, the switch is thrown and the plane does the rest. As the plane increases in velocity, it makes a greater circle and as it circles out it tightens the chain or pulls 20 away from it and in so doing opens the bottom of the cradle and the candy drops through into a net. The party holding the paddle corresponding to the net in which it falls, receives the candy. The power is 25 transferred from the power circuit by two wires through the pipe 15 to the copper rings 28 and from there is connected through slide copper brushes 27 to leads running to counterbalance motor and through support 30 chains 17 to 110 volt motor in plane. A small bell stepdown transformer in the plane receives the 115 or 110 volts and distributes at 4 volts to miniature lights on plane, which illuminate plane in flight. The plane is 35 capable of attaining a speed of eight to ten miles and an eighteen foot circle, but the candy release chain acts as a governor to any circle desired and can be adjusted to deposit the candy at certain speeds. For 40 example, when business is not rushing, a long play can be made, which attracts attention and the plane can make six, eight, ten, or as many more circles as the operator desires, then on the other hand, if he has a 45 crowd and wants to have quick play, he can adjust it by shortening the trip or conveyer chain, so that the plane will drop the candy at a circle and a half or two circles and get the money. The structure is so simple that 50 for the entire apparatus, the weight should not normally exceed 125 pounds. In assembling, the metallic inserts into the pole 15

are inserted and dropped into the pipe 14, the cross-arm is then screwed to the protruding steel bar, the brush is adjusted and the 55 throwing of a switch starts the plane in a revolving motion and lights up at the same time. There is not a gear or any other means interconnecting the driving mechanism with any invisible source, the whole 60 being entirely in the open and is air driven. Normally, a 16' x 16' space is required to operate, otherwise the plane or gondolas will strike any obstruction in the path. By reason of the visibility of the game, it becomes 65 a legal amusement, both interesting and instructive. The netted wheel is in four parts to allow the easy packing for shipment. The support and brace 24 and 25 guard against the pole snapping or bending under flying 70 weight.

What we claim is:

1. In a game, separately indicated receptacles, tokens corresponding to the indications on said receptacles to be distributed, a 75 revoluble member provided with an air propeller and provided with a prize to be released by a trip and means for electrically operating said propeller and means for operating said trip, said trip operating means 80 including a member controlled by the centrifugal force of said revoluble member.

2. In an airplane having an orbital movement, for amusement purposes, a cradle and means for opening the bottom of said cradle 85 upon a predetermined speed of said airplane, said means including a bottom mounted upon a lever and counterbalanced by a weight, and means interconnecting the weighted end of said lever with a member 90 near the center of the orbit, and means for suspending said airplane whereby upon increased velocity the centrifugal force of the airplane will cause the said interconnecting member to elevate the said weight and open 95 the bottom of said cradle.

In testimony whereof we affix our signatures in presence of two witnesses.

ERWIN AUFFURTH, JR.
ERICK HJERPE.
